(57) CLAIM

The ornamental design for a pet playpen as shown and described.

DESCRIPTION

FIG. 1 is a perspective view of the pet playpen showing my new design;

FIG. 2 is a front perspective view thereof;

FIG. 3 is a rear perspective view thereof;

FIG. 4 is a right side perspective view thereof;

FIG. 5 is a left side perspective view thereof;

FIG. 6 is a top view thereof; and,

FIG. 7 is a bottom view thereof.

The broken lines illustrate portions of the pet playpen that form no part of the claimed design.

1 Claim, 7 Drawing Sheets
